RIVET SETTING MACHINE

Edwin B. Stimpson and Julius Gualtieri, Brooklyn, N. Y., assignors to E. B. Stimpson Company, Brooklyn, N. Y., a corporation of New York

Application February 20, 1933, Serial No. 657,482

9 Claims. (Cl. 218—2)

The present invention relates to improvements in rivet setting machines and more especially in rivet setting machines of the treadle operated type.

5 The present improvements relate to simplification and to power mechanisms of a treadle operated rivet setting machine wherein it is particularly desirable to conserve the energy of the operator and to apply the same most efficiently 10 to produce the rivet setting operation. Machines of this type are usually operated by operators of limited mechanical knowledge and skill, and, therefore, it is desirable that such machines shall be as simple in construction as is commensurate 15 with strength and durability which the usage of these machines require. It is particularly desirable that machines of this type be of such design as to facilitate economies in manufacture because in the majority of cases, the machines 20 are leased without fee to rivet users by rivet manufacturers whose compensation is received through the sale of rivets. Therefore, machines which are expensive to manufacture result in a very large outlay of capital by the rivet manufacturer, and any economy which may be produced by novel designs is of extreme importance 25 in this type of device.

Devices of this character must be provided with feed mechanism and in the present case a primary 30 element in the feed construction is a rivet feeding cup. It has been the practice of the art heretofore to utilize cups manufactured by machining an iron casting. These cups are changed from time to time by the user when different sized 35 rivets are used and the cups are often dropped by the operator during such changes. Cast iron cups break when dropped on hard floors, and the machine operations in producing the cast iron cup is an expensive proceeding. Furthermore, cast 40 iron cups are heavy and since the cup is started and stopped by each treadle operation, a substantial amount of energy of the operator goes into the force required to overcome the inertia of the heavy cup at each operation.

45 The present invention comprises a cup having a drawn metal cup portion inserted within a machined metal rim and provided with a staked tubular hub. In the manufacture of this novel cup, the cup portion is formed of thin sheet metal drawn to shape. The hub is cut from a small wrought metal tube, and the rim is a section from a large wrought metal tube in which are machined the rivet feeding slots and a shoulder 50 to receive the rim of the pressed metal cup. The parts are then assembled by pressing operations

and the result is a cup of malleable metal of weight less than one-half the weight necessary to provide a cast cup of the same strength. Furthermore, since the metals of the assembled cups are malleable, they are not easily broken by dropping or being subjected to rough usage, and the cups 5 are very economical to manufacture.

Another feature of the present invention is the manner by which the treadle power is applied through a double toggle link mechanism which 10 drives the setting head against a stationary anvil. In this way, the movement of the setting plunger is a rapidly decelerated movement in that the initial movement of the plunger is relatively 15 rapid as it moves toward the anvil and then it slows up at the time when the rivet setting operation occurs so that the movement of the plunger is slight but it applies a very great pressure to the rivet at the moment of setting the same.

20 Another feature of the present invention is a simplified ratchet construction comprising duplicate pressed metal members which when assembled form a light weight ratchet wheel of adequate strength to operate the feed cup.

25 Another feature of the present invention is the rivet holding cup jaws which comprise a single strip of spring material provided with complementary rivet cups to hold a rivet in position to be set.

30 Another feature of the present invention relates to the feeding head frame and hopper which are formed of a single piece of light weight sheet metal, thereby combining sturdiness with economy of weight and also providing a structure 35 which may be very economically manufactured.

35 A further object of the present invention is the construction of an open feed hopper located adjacent the feed cup whereby a substantial part of the top of the rim of the feed cup at the top 40 thereof is unobstructed by guides so that any rivets which may be carried upwardly by the feed cup are released to fall back into the cup for subsequent feeding operations.

45 The above generally described mechanisms together with other features will be more specifically described in the detail specification herein-after following.

50 It is realized that the present inventions may be embodied in structures other than those specifically disclosed herewith, and, therefore, it is to be understood that the disclosure is to be considered as illustrative and not in the limiting sense.

Fig. 1 is a side elevation of the complete ma- 55

chine showing the pedestal broken to shorten the vertical height of the view.

Fig. 2 is a view of a front elevation of the head of the machine shown in Fig. 1.

5 Fig. 3 is a detail front elevational view of the feed hopper frame.

Fig. 4 is a side elevational view of the feed hopper frame.

10 Fig. 5 is a front elevational view of the feed cup.

Fig. 6 is a side elevational view of the feed cup showing a portion thereof in section.

Fig. 7 is a sectional view through the rim of the feed cup shown in Fig. 6.

15 Fig. 8 is a plan view of one of the ratchet members.

Fig. 9 is an elevational view of the ratchet member shown in Fig. 8.

20 Fig. 10 is an elevational view of two members of the character shown in Figs. 8 and 9 assembled face to face to comprise a complete ratchet wheel.

Fig. 11 is a side view of the rivet spring cup.

Fig. 12 is a front view of the rivet spring cup.

25 Fig. 13 illustrates a blank from which the rivet spring member is formed.

Fig. 14 illustrates the double toggle mechanism for the rivet setting punch.

Referring now more especially to Figs. 1 and 30 2, a hollow pedestal frame 1 is provided with a base 2 in which a treadle 4 is secured by a pivot shaft 5. A coil spring 6 is anchored to one end of the pedestal frame and at the other 35 end of the treadle 4 to normally hold the treadle upward against an adjustable screw stop 7 mounted on the front of the pedestal frame 1 to provide an adjustable limit stop for the upper position of the treadle. A similar screw stop 8 is mounted beneath the treadle in the base frame 40 2. A head frame 9 is bolted to the pedestal frame 1 and carries the feed mechanism and the rivet setting devices. A main link 10 connects the treadle 4 with a main toggle lever 11 which is pivoted on a short shaft 12 in the head frame 9. A main toggle link 14 through a pivot 45 shaft 13, connects the main toggle lever 11 with a secondary toggle lever 15 mounted on the operating shaft 16 for the rivet feed. A secondary toggle link 17 connects the secondary toggle lever 15 with the plunger which carries the rivet setting head. By referring to Fig. 14, it will be observed that when the treadle operates to pull the main link 10 downward to its limit of movement, that the pivot of the main toggle lever 11, the connection between this toggle lever 11 and the main toggle link 14, all assume a straight line and at the same time the pivot of the secondary toggle lever, the secondary toggle link 17 and the axis of the plunger 18 also assume a straight line. The operation of the main toggle and the secondary toggle produce a very powerful pressing action relative to the lower limit of stroke of the plunger 18. The operation of the toggles and the plunger is practically a free movement until the rivet setting operation begins at which time the main toggle and the secondary toggle are approaching a straight line conclusion of movement, at which time the operator's force on the treadle is very effective to apply great pressure to the rivet setting mechanism.

50 The head frame 9 is provided with a strong extension anvil arm 19 carrying an anvil 20 which is mounted for vertical adjustment by 55 means of the lock nut adjustment screw 21.

The head frame 9 also carries a sheet metal feed frame 22 which is provided with a feed hopper 24 as an integral part of this feed frame. The sheet metal feed frame is provided with a circular recess 25 and with a flange 26 which is adapted to be positioned adjacent the periphery of the rim 27 of the feed cup 28 which is mounted on the operating shaft 16 with the hub 29 of the feed cup 28 frictionally pressed against the bottom of the recessed portion 25 of the feed hopper frame by a spring spider 30 which is seated beneath the removable wing nut 31. This construction facilitates removal of the feed cup 28 when it is desired to change cups for different types and sizes of rivets. It also provides a friction coupling between the rivet feed cup 28 and the operating shaft 16 so that there is no danger of breakage if the rivets jam the feed cup. The feed hopper frame also is formed with an extension curve 32 which leads to a curved arm 34 that forms the base of the trackway for the rivets. A semi-circular sheet metal guide 35 is mounted on the curved extension 32 by spacers 36 comprising small washers through which securing rivets 37 extend. Sheet metal arm guides 38 and 39 are secured to the curved arm 34 by means of similar securing rivets 37 and spacers 36. The lower end of the curved semi-circular guide 35 is angularly inclined at 40 and the upper end of the arm guide 39 is correspondingly inclined at 41 to provide a junction portion between the semi-circular space 42 between the rim 27 of the cup 28 and the semi-circular guide 35. This space 42 extends into the inclined space or rivet track 44 which leads to the space 45 forming the vertical track between the guides 38 and 39. The lower end of the vertical track 45 is bridged by the rivet holder spring cup 46 (see Figs. 1, 2, 11, 12, and 13). This spring cup is formed from a blank of spring material provided with a pair 40 of spring arms 47 and 48 which are connected by a bridge 49 that leads to extensions 50 and 51. These extensions 50 and 51 are preferably riveted through the curved arm 34 of the feed frame 22 in such manner that the spring cup 45 members 52 and 54 are in the path of the rivet setting head 55 which is carried on the plunger 18.

55 It is desirable that rivets shall be fed one at a time to the rivet cup 46 and to this end, a feed arm 56 is mounted about half way up on the curved arm 34 of the feed frame. This feed arm is pivoted on a stub screw 57 which may comprise one of the mounting screws extending through the feed frame into a boss 58 on the head frame, the other securing member being a mounting screw 59 which passes through the arm guide 38, a suitable spacing washer and into the boss 58. The upper end of the feed frame is held in position by extending over the main shaft 16 and being forced against the top of the head frame by the spring spider 30 which holds the feed cup in position.

60 Referring now back to the feed arm 56, the front end of this feed arm is provided with a finger 60 that normally extends into the vertical track 45 for the rivets. The other side of the feed arm is provided with a curved surface 61, the center of which comprises the axis of the stub screw 57. A rivet pocket 62 is provided between 65 the finger 60 and the curved surface 61. The power end of the feed arm 56 is connected by a bent offset link 64 secured to the connection between the main toggle link and the secondary toggle lever so that when the toggle operates, the 70

75

feed arm or cut-off 56 is oscillated. The rivet pocket 62 is of such size and shape as to accommodate the stem of a single rivet. When the cut-off or feed arm 56 is oscillated, the finger 61 moves downwardly and the curved stop surface 62 swings across the vertical track 45 to intercept the vertical movement of the rivets in the feed track 45 above the single rivet which has been resting on the finger 60. Continued movement of the cut-off arm removes the finger 60 from the path 45 and permits the selected single rivet to fall downwardly in the lower portion of the track 45 and to drop off of the track into the spaced apart spring cup members 52 and 54 with the head of the rivet supported in the cups and the stem of the rivet extending downwardly in a vertical direction between the spring arms 47 and 48 of the spring cup holder 56 so that when the rivet setting head 55 descends, it will descend directly over the rivet and cam the spring arms 47 and 48 outwardly, thus releasing the rivet and carrying the same downwardly against the setting anvil 20.

In the operation of the device, it is desirable that the feed cup 28 shall be given an intermittent rotating movement. This is accomplished by a ratchet pawl 65 mounted on the pivot shaft 13 connecting the main toggle link 14 with the secondary toggle lever 15. This pawl engages ratchet teeth 66 on the ratchet wheel 67 which (Figs. 8, 9, and 10) is formed of two stampings of sheet metal. These stampings are identical and comprise a blank having turned in teeth members 66 which preferably are of an uneven number so that when two of these blanks are set face to face, the ends of the teeth 66 on one blank comes opposite solid metal on the other blank. These blanks are also provided with outward turned rims 68 to form a flanged guide for the pawl 65. The ratchet wheel blanks are also provided with a shaft opening 69 which fits over the main shaft 16 so that when the ratchet wheel is operated, the shaft 16 is turned.

It will be observed that the space adjacent the feed hopper 24 on the rim 27 of the feed cup 28 is an open space not associated with rivet guides. This open space facilitates the automatic gravity removal of any rivets which may be carried outwardly during the operation of the feed cup 28.

The rivet setting device herewith disclosed is economically manufactured, efficient in the use of manual power to set rivets and is sturdy in construction. The construction of the operating parts, particularly the rivet feed cup is such that light weight metal may be used, and, therefore, the operator wastes little power in overcoming inertia of heavy moving parts. Furthermore, the entire feed mechanism is of such light weight sturdy construction that the removal of the stub screw 57, the mounting screw 59 and the wing nut 31 releases the entire rivet feeding device from the machine so that it may easily be replaced by one of a different size for handling different types and kinds of rivets.

What we claim is:

1. A device of the character described comprising a frame, a main shaft carried by said frame, a rivet feeding cup mounted on said main shaft, a friction clutch operatively connecting said cup with said main shaft, a ratchet wheel mounted on said main shaft, a manually operable member for operating said device, an anvil, a plunger cooperating with said anvil to set rivets, a plunger operating lever pivoted on said main shaft, a pivot shaft connecting said lever

with linkage mechanism leading to said manually operable member, and a ratchet pawl mounted on said pivot shaft and adapted to engage the teeth of said ratchet wheel whereby said main shaft is rotated when said plunger is operated. 5

2. A device of the class described comprising a frame, a manually operable member adapted to apply manual forces to operate said device, an anvil, a plunger adapted to cooperate with said anvil to set rivets, a main shaft carried by said frame, a rivet feeding cup mounted on said main shaft, friction means operatively connecting said cup with said main shaft, a plunger operating lever mounted on said main shaft, link mechanism operatively connecting said manually operable member with said lever, and means connected to said lever to intermittently rotate said main shaft in the rotative direction of movement of said lever when said lever is operated to cause said plunger to set a rivet against 20 said anvil. 10 15

3. A device of the class described comprising in combination a frame, an anvil, a plunger carried by said frame and adapted to cooperate with said anvil to set rivets, means to apply forces to 25 operate said device, a main shaft, a rivet feeding cup carried by said main shaft, and means to intermittently rotate said cup, said rivet feeding cup comprising a notched rivet feeding rim, 30 a sheet metal cup member secured to said rim, and a tubular hub staked to said sheet metal cup. 30

4. In a rivet setting device, the combination of a frame; rivet setting means carried by said frame; rivet feeding devices comprising a sheet 35 metal back frame having a hopper portion integral with said back frame and a substantially vertical rivet chute base integral with said back frame, whereby a single integral piece of sheet metal comprises said hopper, said back frame, 40 and a rivet chute base; a feed cup adapted to cooperate with said back frame; and rivet guides carried by said back frame to guide rivets from said feeding mechanism to the rivet setting mechanism. 45

5. In a rivet setting mechanism, the combination of rivet setting means and rivet feeding means; said rivet feeding means comprising a back frame of sheet metal having an integral hopper portion, a segmental flange, and a chute extension; a feed cup adapted to cooperate with said back frame with said flange being adjacent a portion of the rim of the feed cup and with the upper portion of the rim of the feed cup adjacent said hopper being open to permit rivets stuck in said rim to drop into said hopper. 50 55

6. A rivet setting device comprising in combination mechanism for setting rivets, devices to feed rivets to said setting mechanism comprising a plunger, and a spring cup adjacent said setting mechanism to hold individual rivets in the path of said setting mechanism, said spring cup comprising an integral member provided with spring arms and terminating with a pair of cup members arranged on each side of the movement of said plunger, and a bridge integral with said spring arms to provide a passageway for rivet stems. 60 65

7. A rivet setting device comprising an anvil, a rivet setting plunger, feed mechanism including a substantially vertical feed chute, a pivoted rivet selector cooperating with said feed chute to feed rivets one at a time beyond said selector, said selector comprising a finger extending across the feed chute, a rivet pocket adjacent said finger and 70 75

an arcuate cut-off portion adjacent said rivet chute, said arcuate portion being concentric with the pivot of said selector whereby said curved portion swings across said rivet chute when the selector is oscillated to hold back rivets while the rivet in said rivet pocket is released by said finger to move downward in said chute.

8. In a rivet setting mechanism, a spring rivet holder comprising an integral member provided with spring arms terminating in a pair of opposed half cup members with said spring arms acting to normally force said pair of half cup members together, and a bridge member integral with said arms and comprising the support therefor with a passageway leading from said bridge

member and between the bottom portions of said cup members.

9. A feed cup for selectively feeding articles, said feed cup comprising a sheet metal cup member, a feed rim provided on the face thereof with feed notches through which articles to be selected are fed, a shoulder provided on said rim, the edge of said sheet metal cup cooperating with said shoulder on said rim whereby said cup comprises the sole support for said rim, and a tubular hub staked to the back of said sheet metal cup whereby said hub comprises the sole support for said cup, the axis of said hub and said cup being substantially coincident.

EDWIN B. STIMPSON.
JULIUS GUALTIERE.
